Kevin Prince(57) **CLAIM**

The ornamental design for a liquor decanter, as shown and described.

DESCRIPTION

FIG. 1 is a perspective view of a liquor decanter, showing my new design;

FIG. 2 is an exploded perspective view thereof;

FIG. 3 is a front elevational view of FIG. 2;

FIG. 4 is a rear elevational view of FIG. 2;

FIG. 5 is a left-side elevational view of FIG. 2;

FIG. 6 is a right-side elevational view of FIG. 2;

FIG. 7 is a top plan view of FIG. 2 showing the top piece of the liquor decanter offset laterally, for clarity of illustration; and,

FIG. 8 is a bottom plan view of FIG. 7.

The broken lines in FIGS. 7 and 8 depict portions of the liquor decanter that form no part of the claimed design.

The brackets in FIGS. 2-9 show the relationship between the exploded portions of the liquid decanter, and form no part of the claimed design.
